SCREW GRIPPING SCREW DRIVER

Edward T. Dausch, Sparks, Nev.

Application January 5, 1945, Serial No. 571,425

2 Claims. (Cl. 145—52)

1

The present invention relates to new and useful improvements in screw drivers, and more particularly to means carried by the screw driver for holding a screw or other fastening device while being turned by the screw driver.

An important object of the present invention is to provide screw-gripping means at the end of the screw driver and operable for engaging and releasing the screw from a position at the handle of the screw driver.

A further object is to provide a tool of this character of simple and practical construction, which is efficient and reliable in operation, relatively inexpensive to manufacture and otherwise well adapted for the purposes for which the same is intended.

Other objects and advantages reside in the details of construction and operation, as more fully hereinafter described and claimed, reference being had to the accompanying drawings forming part hereof, wherein like numerals refer to like parts throughout, and in which

Figure 1 is a top plan view.

Figure 2 is a longitudinal sectional view taken substantially on a line 2—2 of Figure 1.

Figure 3 is an enlarged fragmentary side elevational view of the screw holder at the end of the screw driver.

Figures 4, 5 and 6 are transverse sectional views taken respectively on the lines 4—4, 5—5 and 6—6 of Figure 2.

Referring to the drawings in detail, wherein for the purpose of illustration I have disclosed a preferred embodiment of the invention, the numeral 5 designates the shank of the screw driver having the flat screw-engaging blade 6 at its outer end and having a handle 7 suitably secured at its inner end.

A pair of rods 8 are positioned longitudinally at opposite sides of the shank 5, the inner ends of the rods being slidably received and extending longitudinally through the handle 7 and inserted through a disc 9 reciprocably mounted in a chamber 10 formed in a cap 11 threaded on the outer end of the handle 7, the outer end of the cap being spaced from the adjacent end of the handle to form the chamber 10, as will be apparent from an inspection of Figure 2 of the drawings. A push-button 13 is slidably mounted in a central aperture in the top of the cap 11 this button having a lower reduced section 14. The rods 8 have their upper ends bend inwardly at right angles to their main bodies, and these ends are gripped intermediate the slidable disc 9 and a washer 12 which abuts the shoulder intermediate the re-

2

duced lower end 14 and the main body 13 of the push-button. A diametrically disposed pin 15 is also positioned at the shoulder intermediate the lower reduced end 14 and the main body 13 of the push-button, where it is abutted by the washer 12, and this pin is adapted to abut the top of the cap 11 to limit upward movement of the push-button 13.

The disc 9, push button 13 and rods 8 are yieldably held in an upwardly or outwardly disposed position by means of a coil spring 16 mounted between the outer end of the handle 7 and the disc 9.

The lower or inner ends of the rods 8 are slidably mounted in a washer or annular member 17 welded or otherwise suitably secured adjacent the lower end of the shank 5.

A pair of spring fingers 18 have one end secured to the lower ends of the rods 8 by means of pins 20 or rivets 19 and project longitudinally at opposite sides of the blade 6 and with their lower ends bent inwardly to form jaws 20 and provided at their inwardly projected end portions with V-shaped notches 21 adapted for receiving the shank of a screw or similar fastening device 22, whereby to grip the screw under the head thereof, as indicated in Figure 2 of the drawings.

The lower end of the shank 5 of the screw driver is formed at diametrically opposite sides with rounded knobs or lugs 23 engaging the inner surfaces of the fingers 18 whereby to separate or expand the jaws 20 upon a downward movement of the rods 8 and the fingers 18, the jaws 20 and spring fingers 18 returning to their normal positions upon an upward movement of the rods 8.

Accordingly, by depressing the plunger 13, the rods 8 and fingers 18 will be moved downwardly relative to the screw driver to separate the jaws 20 in order to receive the screw 22 between the jaws and upon releasing the plunger 13, the spring 16 will move the rods 8 and fingers 18 upwardly to cause a gripping engagement of the screw with the jaws 20.

While I have illustrated the invention adapted for use in holding screws or similar fastening devices, it will be apparent that the device may also be used for gripping and applying nuts onto bolts.

It is believed the details of construction and manner of use of the device will be readily understood from the foregoing without further detailed explanation.

Having thus described the invention, what I claim is:

1. In a screw driver and a screw-holding at-

tachment therefor, the screw driver having a handle and a screw-engaging shank projecting from one end of the handle, and the attachment comprising a pair of rods disposed on opposite sides of and extending longitudinally of the shank, said rods being slideable in said handle and having one end projecting beyond one end of said handle, the other end of said rods projecting beyond the other end of the handle, a guide plate on said shank having holes through which the rods extend slideably, a hollow cap secured upon said one end of said handle and enclosing a push-button chamber and having an opening through the end thereof, a push button projecting through said opening, a washer fixed upon the push button, inwardly-directed portions upon said one end of the rods and engaging the innermost face of said washer, a disc having a pair of spaced holes through which said rods extend and being disposed inwardly of and abutting said inwardly-directed rod portions, a spring disposed in said chamber between the disc and the handle, a pair of opposed spring fingers fixed in end slots in the other end of said rods beyond said guide plate and being biased toward said screw-engaging shank, the free end of said fingers being provided with screw-engaging jaws, and a pair of round knobs or lugs fixed upon both sides of said screw-engaging shank in longitudinal alignment with said rods and engaging the adjacent surfaces of said spring fingers, whereby depression of said push button causes longitudinal movement of said rods and said spring fingers relative to said shank and divergence of said spring fingers.

2. In a screw driver and a screw-holding attachment therefor, the screw driver having a handle and a screw-engaging shank projecting from one end of the handle, and the attachment comprising a pair of rods disposed on opposite sides of and extending longitudinally of the

10
1520
25

shank, said rods being slideable in said handle and having one end projecting beyond one end of said handle, the other end of said rods projecting beyond the other end of the handle, a guide plate on said shank through which the rods extend slideably, a hollow cap secured upon said one end of said handle and forming with said handle a chamber, a vertically-disposed push button slideably mounted in said chamber and projecting from the latter, inwardly-directed portions upon said one end of the rods and operatively secured to said push button, spring means disposed in said chamber and operatively connected to said one end of said handle and said push button for biasing the push button into its projected position, a pair of opposed spring fingers fixed to the other end of said rods beyond said guide plate, the free end of said fingers being provided with screw-head-engaging jaws, and a pair of knobs fixed upon both sides of said screw-engaging shank in longitudinal alignment with said rods and engaging the adjacent surfaces of said spring fingers, whereby depression of said push button causes longitudinal movement of said rods and said spring fingers relative to said shank and divergence of said spring fingers.

EDWARD T. DAUSCH.
